TOY

Filed April 26, 1930

Paul T. Pino.

Inventor:

By Clarence O'Brien, Attorney

UNITED STATES PATENT OFFICE

PAUL THOMAS PINO, OF BATON ROUGE, LOUISIANA

TOY

Application filed April 26, 1930. Serial No. 447,742.

This invention appertains to new and useful improvements in toys and more particularly to a novel toy resembling a pistol for projecting rubber bands.

5 The principal object of this invention is to provide a toy pistol provided with novel trigger means for releasing a rubber band or similar projectile.

Other important objects and advantages of 10 the invention will become more apparent to the reader after the invention proceeds hereinafter.

In the drawings:—

Figure 1 represents a side elevational view 15 of the novel toy with a rubber band stretched thereon.

Fig. 2 represents a top plan view of the toy with the parts set as shown in Fig. 1.

Fig. 3 represents a perspective view of the 20 trigger.

Fig. 4 represents a perspective view of the rocker arm.

Referring to the drawings wherein like numerals designate like parts, it can be seen 25 that the novel toy includes a body generally referred to by the numeral 5 and generally resembling a pistol. This body comprises a shank or stock portion 6, a breech portion 7 and a barrel 8, the free end of the barrel 8 being provided with a notch 9 into which the rubber band 10 may engage in the manner 30 shown in Fig. 1.

Pivots secured to the breech portion 7 of the body 5 is the L-shaped trigger 11. 35 The heel portion of this trigger 11 is provided with an opening 12 for receiving the pivot member 13. One end of the trigger 11 is provided with a laterally disposed lug 14 which is engageable within the bifurcated 40 end 15 of the rocker arm 16.

The rocker arm is provided with an opening 17 at its intermediate portion to receive the pivot member 18 which is driven into the body 5 forwardly of the breech portion 7.

45 The upper end of the body 16 will protrude above the top of the barrel 8 when the lug 14 is engaging within its bifurcated end 15. When the trigger and rocker arm are thus engaging, the rubber band 10 is stretched between the notched end of the barrel and the

upper end of the rocker arm as in the manner shown in Fig. 1.

It can now be seen that when the trigger is pulled, the lug 14 will be disengaged from the bifurcated end of the rocker arm 16 thus 55 releasing the rocker arm 16 and permitting the rubber band 10 to spring forwardly and project beyond the notched end of the barrel 8.

It can be seen that the foregoing specification sets forth the invention in detail and it is to be understood that numerous changes in the shape, size and materials may be resorted to without departing from the spirit and scope of the invention as claimed hereinafter.

Having thus described my invention, what I claim as new is:—

A toy pistol of the character described comprising a body simulating a pistol barrel 70 and handle, an L-shaped trigger, said trigger being pivotally secured to the body at the heel portion of the said trigger, one end of the trigger being provided with a laterally extending lug, a rockable member on the body, one end of the rockable member being provided with a notch for receiving the lug on the trigger, a rubber band, said band being stretchable between the upper end portion 75 of the rockable member when the lug is engaged in the notch at the opposite end thereof, and with the barrel portion of the body 80 at the muzzle end thereof.

In testimony whereof I affix my signature.

PAUL THOMAS PINO.
